BUILDING PANEL

Arthur L. Kehm, Harrisburg, S. Dak., assignor to
 Meinzer & Kehm Company, a corporation of
 South Dakota

Application January 5, 1932, Serial No. 584,889
 Renewed December 18, 1934

1 Claim. (Cl. 20—1.4)

This invention relates to building panels especially adapted to be used in constructing silos, and it consists in the novel features hereinafter described and claimed.

5 An object of the invention is to provide a panel of the character indicated having its exterior surface cross-ribbed, having beveled end surfaces disposed beyond the side edges of the panel and lug plates mounted upon said ribs and adapted to receive bolts which connect the abutting edges of adjacent panels together in the silo's structure. The inner surfaces of the panels are smooth and therefore the inner wall surfaces of the silo structure is smooth as the ribs are at the exterior 10 surfaces of the panels. Upon each panel, the upper rib has an upper surface lying in a plane above the upper edge of the panel, an intermediate rib disposed approximately midway between the upper and lower edges of the panel and a lower rib spaced above the lower ledge of the panel. The arrangement is such that the panels which abut each other vertically interlock with each other.

In the accompanying drawing:

Figure 1 is a fragmentary side elevational view 25 of the silo structure showing the panels arranged therein.

Figure 2 is a fragmentary edge view of adjacent panels connected with each other.

Figure 3 is a side elevational view of a silo made 30 up of the panels.

Figure 4 is a top plan view of the silo as shown in Figure 3.

Figure 5 is a fragmentary detailed sectional view 35 showing the interlocking edges of vertically abutting panels.

The panel 1 consists of a number of pieces of tongue and groove boards intersecting each other, and the panel is rectangular in side elevation. Ribs 2 are applied to the outer surface of the panel and the said ribs are provided with beveled end surfaces 3 which are disposed beyond the side edges of the panel 1 as best shown in Figure 2 of the drawing. The upper rib 2 is disposed above the upper edge of the panel 1. The lower rib 2 has its lower surface disposed above the lower edge of the panel 1 and the intermediate rib 2 is approximately midway between the upper and lower edges of the panel. All of the said ribs are provided at their ends with plates 4 having outstanding lugs 5. Bolts 6 pass through lugs 5 whereby the vertical edges of adjacent panels may

be held in close contact with each other and the ends of the corresponding ribs of the adjacent panels are held in close contact with each other as shown in Figure 2 of the drawing. As shown in Figure 5 of the drawing, the rib 2 which is attached to the lower panel 1 overlaps the lower portion of the panel which is above so that the intermediate portions of the panels cannot bulge or spring with relation to each other. When the panels are assembled in the form of a silo, the 10 inner wall surface thereof is smooth and the ribs being disposed at the exterior of the panels prevents the structure from twisting or warping out of shape. This gives a smooth surface on the inside of the silo and the ribs around the outside 15 form bands that assure rigidity. The building may be used for storing grain and when a small number of panels is used, houses for hogs or chicken brooders may be erected. Any number of panels may be added to the structure or subtracted therefrom at any time. The advantages gained by using such panels are that silos and similar buildings may be constructed at low cost. They may be quickly erected and may be increased or diminished in size readily as desired.

The panels may be arcuate in shape and in which case a completed silo would be in the form of a circular building, on which all corners have been eliminated.

Having described the invention, what is claimed is:

A building wall consisting of panels the inner surfaces of which are smooth, ribs applied to the outer surfaces of the panels adjacent the upper and lower edges and having beveled extremities 35 formed at the ends of the panels with the angle of the bevel so disposed that the ends of the ribs extend beyond the panels, lug plates attached to the ribs adjacent the beveled ends, bolts detachably connecting the lug plates of adjacent panels 40 together, the upper ribs having their top faces disposed above the plane of the upper edges of the panels and the bottom ribs having their lower faces correspondingly disposed with reference to the lower edges of the panels to effect rib overlap 45 of vertically adjacent panels while bringing the adjacent ribs of the same into face contact, and bolts passing through said adjacent ribs to secure the same together.
